John Sealy Jr.

JOHN SEALY, JUNIOR, OF NEWARK, NEW JERSEY.

Design No. 3,322, dated January 5, 1869.

DESIGN FOR THE ORNAMENT OF A HAT.

The Schedule referred to in these Letters Patent and making part of the same.

To all whom it may concern:

Be it known that I, JOHN SEALY, Junior, of the city of Newark, and county of Essex, and State of New Jersey, have invented or produced a new Design of an Ornament for a Hat or Cap, of which the following, taken together with the drawings accompanying this specification, as part thereof, is a full, clear, and exact description.

A metallic plate, with shell-like radiating corrugations starting from a circular plate or button as a centre, terminates at its wide end in two sections of a

circle, forming three points, the centre point projecting farther, in proportion, than the two side points. This ornament is placed on the side of the hat, in contact with the band.

What I claim as my design, and desire to secure, is—
The peculiar form and design of the metallic plate &c, as herein specified and shown.

JOHN SEALY, JUNIOR.
